N. KAPLAN,
SHIRT.

Patented Apr. 20, 1920.

UNITED STATES PATENT OFFICE.

NATHAN KAPLAN, OF COVINGTON, GEORGIA.

SHIRT.

1,337,917.

Specification of Letters Patent. Patented Apr. 20, 1920.

Application filed November 4, 1918. Serial No. 261,062.

To all whom it may concern:

Be it known that I, NATHAN KAPLAN, a citizen of the United States, residing at Covington, in the county of Newton and 5 State of Georgia, have invented a new and useful Shirt, of which the following is a specification.

The device forming the subject matter of this application, is a shirt, and one object 10 of the invention is to provide novel means whereby the shirt will be prevented from working upwardly within the trousers of the wearer when a belt is worn, the construction being such that the garment will shape 15 itself readily to the body of the wearer.

It is within the province of the disclosure to improve generally and to enhance the utility of devices of that type to which the present invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in front elevation, a portion of a shirt whereunto the device forming the subject matter of this application has been applied, parts being broken away; 35 Fig. 2 is a section on the line 2—2 of Fig. 1, one of the arms having been looped up and secured to the front of the shirt; Fig. 3 is a fragmental front elevation showing a modified form of the invention; and Fig. 4 40 is a section on the line 4—4 of Fig. 3.

In carrying out the invention as disclosed in Figs. 1 and 2, there is provided a shirt 1 having a short tail 2, and including a front 3, reversely curved on its lower edge, to 45 form a reduced tongue 4, the front 3 consisting of flaps 5 overlapped on each other, and attached to each other by means of buttons 6 or in any other suitable way. The intermediate portion of a U-shaped strip 7 is 50 secured at 8 to the tail of the shirt, the strip 7 including approximately parallel arms 9, the longitudinal edges of which are turned inwardly and secured to form reinforcements 10, the ends of the arms 9 are folded 55 backwardly, and being secured as shown at

11, to reinforce the terminals of the arms. Owing to this particular construction employed at the point indicated, the ends of the arms 9 will be of unusual strength, and will be well adapted to withstand the pull imposed thereon, when button holes 12, in the ends 11 are engaged with buttons 14 on the front 3 of the shirt, both the buttons and the button holes being duplicated, vertically, to provide for adjustment. Since a U-shaped member 7 is employed, constructed as described, the garment will shape itself readily to the body of the wearer, and will prevent an upward creeping of the shirt, as will be clearly understood by those skilled in the art.

Referring to Figs. 3 and 4, there is shown a shirt 15 having a tail 16 provided with an extension 17 carrying button holes 18 adapted to be engaged with buttons 19 on the flaps 20 of the front 21 of the shirt, the front of the shirt being reversely curved, at its lower edges, as shown at 22, to form a reduced tongue 26. The free end of the extension 17 is folded backwardly on itself as shown at 23, and is secured to the body portion of the extension, to fashion a reinforcement, as hereinbefore described. The operation of the shirt shown in Figs. 3 and 4 does not differ materially from the operation of the shirt shown in Figs. 1 and 2, aside from the advantages arising out of the use of the U-shaped strip 7.

Having thus described the invention, what is claimed is:—

90 A shirt comprising a tail and a front; a U-shaped strip including an intermediate portion and arms at the ends of the intermediate portion, the arms and the intermediate portion being integrally formed, the intermediate portion being secured to the tail, the longitudinal edges of the arms being folded inwardly and being secured to form reinforcements, the free ends of the arms being folded backwardly on the reinforcements and being secured thereto; and means for connecting the free ends of the arms detachably with the front of the shirt.

95 In testimony that I claim the foregoing as my own I have hereto affixed my signature 100 in the presence of two witnesses.

105 NATHAN KAPLAN.
